UNITED STATES PATENT OFFICE

2,631,780

BALL CONTROLLED REGISTER

Samuel Branner, Chicago, Ill.

Application September 12, 1949, Serial No. 115,199

1 Claim. (Cl. 235—91)

1

My invention relates to toy basketball games, and more particularly to the registers for the scores therein, as covered in my Patent No. 2,192,430, issued March 5, 1940, and one object of the present invention is to provide a register which is automatic.

A further object is to modify the structure in my patent in a simple manner to accomplish the automatic control of the register.

With the above objects in view, and any others which may suggest themselves from the description to follow, a better understanding of the invention may be had by reference to the accompanying drawing, in which—

Fig. 1 is a front elevation of the game;

Fig. 2 is a rear elevation;

Fig. 3 is an edge view from the right hand side of Fig. 1: and

Fig. 4 is an enlargement of a detail in the central bottom portion of Fig. 3.

In accordance with the foregoing, it may be stated that the general structure of the game is the same as in the patent. Thus, 3 is the frontal plate, 5 is the ratchet wheel, 6 the top hanger, 7 the rear hook thereof, 10 the pendent plate, 11 the gong, 11' is the pivoted lever, 25 the check pawl, and 40 the control wire.

Whereas the control wire was operated manually in the patented structure, I now employ the pivoted lever 11' to induce this action. Thus, the control wire 40 is formed with a rounded bottom bend 50 and continued forwardly in a rising direction as indicated at 52, to terminate with a portion 54 which passes freely through an opening 55 in the lever 11'. The end portion 54 of the control wire receives an assembled grommet 57, whose threaded shank 58 passes freely in a downward direction thru the opening 55 to receive a nut 60 at its bottom end. The shank 58 is split from the bottom as indicated at 62, in order that the nut 60 may compress the shank as it is screwed upon the same and be retained on the grommet by the tension of its shank. The grommet is bored centrally as indicated at 65 to tightly receive the end portion 54 of the control wire 40.

The upper portion of the control wire 40 passes through an arched guide 67 carried by the pendent plate 10, and also through an S-shaped guide 68 carried by the plate 3. The wire then takes a shallow lateral bend at 70 in the direction of the ratchet wheel, terminating with a side hook 72 opposite the rim of the same. Fig. 3 shows the position of the control wire 40 under normal conditions, that is, when the game is not being

10 played. Now the lever 11' is in the horizontal position, and the hook 72 of the control wire is high in relation to the ratchet wheel 5, as indicated by the dotted lines in Fig. 2. The control wire 40 in the present case is of spring stock; and its tendency is to ride the top of the ratchet wheel in the dotted line position mentioned. Thus, when the lever 11' is depressed by the game ball, the hook 72 of the control wire 40 pulls down on one tooth of the ratchet wheel, causing the register to advance accordingly, so that the position of the control wire changes to that indicated by full lines in Fig. 2. Now the tendency of the control wire is still to bear against the periphery 15 of the ratchet wheel. However, any chance that the hook 72 may become disengaged from such periphery is counteracted by a vertical rib 75, struck back from the plate 3 in a position adjoining the one occupied by the lowered control wire 40. It follows, of course, that the subsequent rise of the lever 11' will induce the rise of the control wire 40; and the above described 20 tendency of the latter will cause its hook to bear against the periphery of the ratchet wheel and assume its top position in readiness for the next 25 registering movement of the wheel.

It will be apparent that a simple mechanism is provided to procure the automatic register action. Thus, the control wire is in a single 30 piece, both as a spring lever, and as a hook to actuate the ratchet wheel. Further, the wire makes its connection with the lever 11' by means of a relatively short bend and a grommet, which is free to adjust itself to the changing angle of 35 the lever. Further, the present improvement makes a direct connection from the frontally positioned lever 11' to the control wire 40 in rear of the plate 3 by simply forming the wire with the frontal return bend 50 to connect with 40 the lever, this being made possible by locating the latter on the plate 3 rather than below the same, as in my patent. The game is therefore more simple and compact as a result. Further, the improvement is only slightly in evidence in front of the game, so that it does not amount 45 to an impediment or complication; and its operative portion is fully in back of the game and out of the way. Finally, it is apparent that the improved control is made up of only two major parts, which may be produced at low cost.

While I have described the invention along specified lines, various minor changes or refinements may be made therein without departing from its principle, and I reserve the right to employ all such changes and refinements as may

2

come within the scope and spirit of the appended claim.

I claim:

The combination with a game having a support, a frontal lever depressible relative to the same, and a horizontally-journalized ratchet-wheel register carried on the rear side of the support; of a spring control wire depending in rearward direction from the lever and trained upwardly behind the support, the upper end portion of the wire having a side hook over the top of the ratchet wheel and tensioned to normally ride the latter, and the depression of the lever drawing on the control wire and its hook in a manner to impart a part-rotary movement to the register, the lever being pivoted horizontally to the support, and a freely-pivotal connection between the lever and the wire to allow for changes

in the angular position of the lever, said connection comprising an opening in the lever, and a grommet carried by the control wire and freely disposed in said opening.

SAMUEL BRANNER.
